(57) CLAIM

The ornamental design for a panty liner, as shown and described.

DESCRIPTION

FIG. 1 is a top view of the panty liner showing my new design, the bottom view being substantially the same thereof.

FIG. 2 is a right side view of the panty liner shown in FIG.
1, the left side view being substantially the same thereof.

FIG. 3 is a rear view of the panty liner shown in FIG. 1; and,
FIG. 4 is a front view of the panty liner shown in FIG. 1.
